CLAIM

We claim the ornamental design for a firearm trigger, as shown and described.

DESCRIPTION

FIG. 1 is a front perspective view of a first embodiment of a firearm trigger showing our new, original, and ornamental design;

FIG. 2 is a left side view of the embodiment of FIG. 1;

FIG. 3 is a right side view of the embodiment of FIG. 1;

FIG. 4 is a front view of the embodiment of FIG. 1;

FIG. 5 is a rear view of the embodiment of FIG. 1;

FIG. 6 is a top view of the embodiment of FIG. 1;

FIG. 7 is a bottom view of the embodiment of FIG. 1;

FIG. 8 depicts the embodiment of FIG. 1 in an example use environment trigger housing;

FIG. 9 is a perspective view of a second embodiment of a firearm trigger showing our new, original, and ornamental design;

FIG. 10 is a left side view of the embodiment of FIG. 9;

FIG. 11 is a right side view of the embodiment of FIG. 9;

FIG. 12 is a front view of the embodiment of FIG. 9;

FIG. 13 is a rear view of the embodiment of FIG. 9;

FIG. 14 is a top view of the embodiment of FIG. 9;

FIG. 15 is a bottom view of the embodiment of FIG. 9; and, FIG. 16 depicts the embodiment of FIG. 9 in an example use environment trigger housing.

The broken line in the drawings discloses unclaimed portions of the firearm trigger only and forms no part of the claimed design.
